Fig. 1

Fig. 2

FIG. 1 is a front perspective view of the magnetic tape handler showing our design.

FIG. 2 is a left side view of the same.

FIG. 3 is a rear view of the same.

FIG. 4 is a top view of the same.

The essential feature of our design resides in a magnetic tape handler having a front exterior including a recessed control panel, a door extending from one side panel to the other side panel and a flat window in said door substantially as shown.

We claim:

The ornamental design for magnetic tape handler, substantially as shown and described.
